(57) CLAIM

The ornamental design of a bra, as shown and described.

DESCRIPTION

FIG. 1 is a front perspective view of a bra, showing my new design;

FIG. 2 is a rear view thereof;

FIG. 3 is a front view of the bra showing in a first configuration of use on a mannequin bust;

FIG. 4 is a perspective view of FIG. 3;

FIG. 5 is a right side view thereof;

FIG. 6 is a left side view thereof;

FIG. 7 is a rear view of FIG. 3; and,

FIG. 8 is a rear view of the bra showing in another configuration of use on a mannequin bust.

The short dashed broken lines in the drawings depict portions of the bra, that form no part of the claimed design. The long dashed broken lines showing a mannequin bust illustrate environmental subject matter and form no part of the claimed design.

1 Claim, 8 Drawing Sheets
